REMOTE CONTROL SYSTEM

Paul K. Eckhardt, O'Hara Township, Allegheny County, Pa., assignor to The Union Switch & Signal Company, Swissvale, Pa., a corporation of Pennsylvania

Application January 23, 1947, Serial No. 723,739

8 Claims. (Cl. 177—353)

1

My invention relates to remote control systems, and more particularly, to the communication or line circuits for such systems, and has as its principal object the provision of remotely controlled means for enabling the adverse effects of line or apparatus faults to be more promptly overcome.

My invention is particularly adapted for use in connection with centralized traffic control systems for railroads in which codes of impulses are transmitted over line wires extending from a train dispatcher's office or other suitable point of control through a plurality of stations, for selectively controlling track switches and signals at the stations, and for indicating the condition of the station apparatus and reporting train movements or the like at the control office.

As disclosed herein, my invention is applied to a centralized traffic control system of the coded carrier current type such as is shown in Letters Patent of the United States No. 2,350,668, issued June 6, 1944, to George W. Baughman and Norman F. Agnew, for Remote control systems. In the system of this patent, a line circuit which may extend the length of a railroad division is divided into sections by electrical filters at one or more points to prevent the passage of direct current from section to section while permitting the passage of voice or carrier frequency currents to provide communication channels extending over two or more sections or between the end terminals of the line. Each section of the line, in the territory controlled by the centralized traffic control system, is equipped with a central battery line circuit which provides parallel connections to coding units at the stations of the system located in the section. The equipment for each section also includes a coding unit at a suitable control point such as a train dispatcher's office, usually at one end of the line. Each office coding unit is adapted to transmit control codes for governing the track switches and signals at the stations in its section and to receive indication codes reflecting the condition of the controlled devices and for also indicating at the control office, the movements of trains through its section. Each controlled section which is remote from the office is provided with a remote line unit by which the codes of direct current pulses are supplied to or received from the line wires of its section. The remote line units and the office coding units for the remote sections are connected to carrier control units which serve to repeat the codes in both directions over the intervening line wires as carrier

2

current pulses of different frequencies, thereby providing independent channels for two-way communication between the office and the stations in the remote sections.

5 A feature of the system of the patent is the provision of changeover relays CH which enable each carrier control unit to be quickly replaced by a reserve unit, in the event of a fault, the relays CH at the remote control stations being controlled by codes transmitted from the office by the centralized traffic control system.

One object of my invention is the provision of means for suitably controlling the changeover relay at a station remote from the office, in the 10 absence of available coding apparatus controlled over the intervening line wires.

15 A feature of the system as disclosed herein is that the utility of the changeover relays has been greatly extended by arranging them so that 20 they are capable of placing in service spare filters, remote line units or other apparatus, so as to enable a much wider variety of faults to be quickly corrected, and further, by the expedient of adjusting the spare carrier control units to 25 operate with a higher transmitting energy and lower received energy than the prescribed energy levels to which those normally in service are adjusted, so as to enable abnormal attenuation of the carrier line currents to be compensated for 30 by remote control.

It has been found for example that in the 35 event of a broken line wire, the continuity of the carrier current channels is maintained to some extent through the capacity to other wires on the same pole line so that the increased attenuation remains within limits which can be compensated for by the insertion of an electronic repeater or by the expedient above mentioned.

40 A feature of my invention is the provision of means for inserting electronic repeaters in the line circuit, either manually by remote control, or automatically in response to a break in the physical line circuit, in response to the operation of the changeover relays or of other similar relays controllable independently of the changeover 45 relays.

45 A specific feature of my invention is the provision of a direct current circuit of reversible polarity and of variable current strength which 50 is superimposed upon the carrier current channels extending from the office to a remote station, by means of which the integrity of the physical line circuit is continuously detected and indicated at the office, and which provides two 55 independent channels for the manual control

of changeover relays or the like, which relays also operate automatically to insert a repeater or other compensating means in the line, in response to the occurrence of a line fault.

Other objects, features and purposes of my invention will be pointed out as the description proceeds.

I shall now describe one form of apparatus embodying my invention and shall then point out the novel features thereof in claims.

Referring to the accompanying drawings, Figs. 1 to 4, inclusive, taken together, illustrate the line circuit connections for a typical centralized traffic control system embodying my invention. An explanation of the internal circuits or detailed mode of operation of the various apparatus units is not needed for an understanding of my invention, and since these are shown in detail in the Patent No. 2,350,668, or in other patents referred to therein, they are shown here in block form to simplify the drawings, and are identified by legend. The line circuit for the system comprises a pair of line wires Y-Z, which provide a through telephone circuit comprising the sections Y₁-Z₁, Y₂-Z₂, etc., connected by electrical filters which serve to block the passage of direct current from section to section. Certain of the filters, designated VPF, are arranged to pass voice frequencies only, while others, designated "VP and HPF," are arranged to pass voice frequencies and also the higher frequencies used for carrier current transmission.

The centralized traffic control system comprises three independent sets of apparatus identified by the suffixes A, B and C, for communication with the stations adjacent the three line sections Y₂-Z₂, Y₃-Z₃ and Y₄-Z₄, respectively, and their respective control station in Figs. 2, 3 and 4, are connected over the intervening line section Y₁-Y₂ with the corresponding coding units at the office, Fig. 1, by carrier control units CC, as shown. Where reserve apparatus units are provided, the units normally in service are designated No. 1, and the reserve units placed in service by the operation of the changeover relays CH are designated No. 2, and where similar units are provided at the office and stations, those at the office are identified by the prefix "O." The carrier current filters selectively responsive to single frequencies, are designated f₁, f₂ and f₃ for the control code frequencies, and f₄, f₅ and f₆ for the corresponding indication code frequencies employed by the centralized traffic control system.

Control codes for the first C. T. C. section are normally supplied by the office coding unit O_A, Fig. 1 (which corresponds to that shown in Fig. 1B of Patent No. 2,350,668), over back contact f of a changeover relay 1CH, to the CC unit No. O_A1, over a circuit which for simplicity is shown in the drawing as a single line terminated by an arrow to indicate the direction of transmission, and the CC unit No. O_A1 repeats these control codes as pulses of frequencies f₁ over the channel including back contacts b and c of relay 1CH, line wires Y₁ and Z₁ and front contacts b and c of a normally energized changeover relay 4CH, to the CC unit No. 1A of Fig. 2, which causes the remote line unit No. 1A connected thereto to repeat the carrier current control codes as direct current pulses from the line battery 80A, over front contacts d, e, f and g of relay 4CH through a low pass filter "LPF" to the line wires Y₂ and Z₂, from which they are selectively received by

the station coding units of the first section, which are connected through low pass filters LPF across the line wires Y₂-Z₂ as shown in Fig. 3. The control codes for the second and third sections, transmitted by the office coding units O_B and O_C, are repeated by the CC units Nos. O_B1 and O_C1 as pulses of frequency f₂ or f₃ over back contacts of relays 2CH and 3CH, thence over the line wires Y₁ and Z₁ of Fig. 1, back contacts b and c of relays RTP and 4CHP of Fig. 2, through the filter "VP and HPF" No. 1A, over back contacts d and e of relays 4CHP and RTP to line wires Y₂ and Z₂. Normally the codes of frequency f₂ are received over back contacts b and c of relay 5CH by the CC unit 1B, of Fig. 3, which causes the remote line unit connected thereto to repeat them as direct current impulses of current from battery 80B supplied over back contacts d and e of relay 5CH, to the line wires Y₃ and Z₃ for the second section, through a filter LPF and back contacts f and g of relay 5CH, from which they are received by the station coding units for the second section, shown in Fig. 4. The codes of frequency f₃ in line wires Y₂-Z₂ normally pass over back contacts b and c of relay 5CH through the filter "VP and HPF" No. 1B, and thence over back contacts f and g of relay 5CH to line wires Y₃ and Z₃, from which they are normally received over back contacts b and c of relay 6CH by the CC unit No. 1C, Fig. 4, which causes the associated remote line unit to repeat these codes as pulses of direct current from battery 80C to the line wires Y₄ and Z₄ of the third section to govern the station coding units of that section.

Indication codes initiated by the station coding units of the several sections are normally transmitted as direct current pulses to the No. 1 remote line unit for the corresponding section, causing the associated CC unit No. 1 to repeat them as pulses of frequency f₄, f₅ or f₆, which are transmitted through the correspondingly designated filters over the line wires extending to the office where they are received by the appropriate office coding unit, as will readily be apparent.

The changeover relays 1CH, 2CH and 3CH at the office, Fig. 1, are controlled by the levers 1PB, 2PB and 3PB, and indications as to whether the normal or reserve set of apparatus controlled by the office changeover relays is in service is provided by the lighting of an indication lamp 11 or 12, 21 or 22, etc. The changeover relays 5CH and 6CH at the remote control stations for the second and third sections are controlled by the office levers 5PB and 6PB by codes transmitted to the last station of the first or second section, respectively, each of which as shown, is identified by the code call 246, and their condition is indicated at the office by indication codes transmitted from these stations to light the indication lamp 51 or 52, or lamp 61 or 62, all of which corresponds to the arrangement described in Patent No. 2,350,668.

The changeover relay 4CH, Fig. 2, at the remote control station for the first section, and a second relay RT at the same location, are independently controllable by direct current supplied to the line wires Y₁ and Z₁ from a battery 20, Fig. 1, at the office over contacts of the levers 4PB and 7PB, respectively. Relay RT is a biased polar relay which holds its contact a open only when energized by current of normal polarity, and may be released manually to pick up its repeating relay RTP by reversing the polarity of

the current supplied thereto by operation of lever 7PB. Relay RT releases automatically due to its deenergization in the event of a fault such as a broken line wire, in the line section Y1-Z1, to interpose an electronic repeater, shown in Fig. 2, in the carrier current channels which normally extend to section Y2-Z2 through the filters f2, f3, f5 and f6, as shown. Since the repeater units act to pass and amplify the carrier frequencies, it is necessary to cut out the "VP and HPF" filter which would act as a shunt on the repeater. A band pass filter "VPF" is inserted with the repeater to carry the voice frequencies.

Relay 4CH is a marginal relay of the retained neutral type which does not release in response to a reversal of line polarity by lever 7PB, but which may be released manually by reducing the voltage supplied by battery 20, by the operation of the lever 4PB, without releasing relay RT. Relay 4CH upon releasing picks up a repeating relay 4CHP. Relay 4CH also releases automatically in the event of a broken line wire in the line section Y1-Z1, and when released, inserts the spare CC unit No. 2A into the carrier current channels for the first section, to compensate in part, at least, for the increased attenuation of the line currents of frequencies f1 and f4 due to such fault, the spare or No. 2 CC units being normally adjusted as required for that purpose as already explained.

Relays 5CH and 6CH are also arranged to be operated automatically in the event of a broken line wire in section Y2-Z2 or Y3-Z3, respectively, to interpose the No. 2 CC units which they control. Relay 5CH thus is capable of providing automatic compensation for increased attenuation of the currents of frequencies f2 and f5 due to a broken line wire in section Y2-Z2, and relay 6CH functions similarly with respect to frequencies f3 and f6, provided the fault is in section Y3-Z3.

To operate the relays 5CH and 6CH automatically in response to a line fault in the adjacent line section, a repeating relay RP, controlled by the line relay R of the last station coding unit in that section, is provided, together with a slow release station disconnect relay RPP controlled thereby, these relays corresponding to the similarly designated relays shown and described in Letters Patent of the United States No. 2,376,569, granted May 22, 1943, to George W. Baughman, for Remote control systems. Relay RP is energized over normally closed contacts of relays R and RPP and repeats the code operation of relay R. Relay RPP has a release period of about eight seconds and does not release during the normal operation of the system but only when relay R is steadily released, and upon releasing, relay RPP opens the circuit for relay RP and also completes a circuit to energize relay 5CH. When the fault is removed, and relay R is reenergized, relays RP and RPP may be reenergized by the transmission of a control code to pick up the station delivery relay D as explained in Patent No. 2,376,569.

It will be seen, therefore, that means are provided for compensating for one break in the carrier current circuits which extend over only one line section and for compensating for two breaks at different locations in those which extend over two or three sections. If desired, compensation for a third break in the line wires for the channels having three sections may be provided by arranging Fig. 3 like Fig. 2, and include

a second electronic repeater in the circuits for currents of frequencies f3 and f6 in place of a filter. The relay 2RT shown in Fig. 3 provides means for controlling such a repeater, relays 5CH and 2RT being independently controllable in accordance with the positions of levers 5PB and 8PB by codes transmitted to the last station of the first section and received by the station storage unit having the code call 246 as shown, which unit also transmits indications of the condition of the positions of these relays to control the lamps 51, 52 and 81, 82.

The condition of the relays 4CH and RT, of Fig. 2, is similarly indicated by another station storage unit of the first section, having the code call 357 and controlled over the carrier channel having the frequency f4, as shown.

As explained in Patent No. 2,350,668, hereinbefore referred to, the coding units correspond to those of Letters Patent of the United States No. 2,229,249, granted January 21, 1941, to Lloyd V. Lewis, for Remote control systems, except for the line circuit modifications by which they are adapted to parallel operation. The numbered wires leading to the storage units in Figs. 2 and 3 correspond to those of Fig. 7 of the Lewis patent, and the relays controlled by the office storage units in Fig. 1 of the present application correspond to the similarly designated relays of this patent.

Considering now the mode of operation of the protection system of my invention, and assuming first the occurrence of faulty code transmission due to a local apparatus failure or to damage to one of the line-connected filters by lightning. The operator will first energize the office changeover relay for the faulty section, which may remove the fault; if not, he will then actuate the remotely controlled changeover relay at the control station for the section, which generally will result in locating and clearing the fault. The No. 1 carrier current receiving apparatus is normally adjusted to a fixed energy level, and in order to minimize interference with other carrier current channels which may employ the same or other wires on the same pole line, the normal transmission level is limited to about 18 decibels above a one milliwatt base. This value may be temporarily exceeded under emergency conditions, due to the No. 2 units being adjusted to transmit at a higher level and receive at a lower level, and in the case above, the maintainer can readjust the spare CC unit and restore the normal transmission values upon his arrival at the office or at the faulty location, following notification by the operator.

It is obvious that the removal of a fault in the first section allows the remotely controlled relays 4CH and RT for that section to indicate their position, and enables the operator to regain control of the relays 5CH and 2RT to correct a fault in the second section, and to control relay 6CH to correct a fault in the third section.

Assuming next the occurrence of increased line loss in all the carrier line circuits due to a sleet storm, for example, the third section being the first to fail. This fault may possibly be corrected by energizing the office changeover relays, but the preferred procedure is to release relay RT to insert the electronic repeater in the longer circuits, this having the advantage that the normal energy level is not materially exceeded at any point, the energy level being such as to allow normal operation of the units for the first section, but not the succeeding sections.

In the event of a broken line wire in any of the sections, the changeover relays at the remote ends of the sections are actuated automatically. If the break is in section Y1—Z1, relays RT and 4CH are released and as already explained, the increased attenuation of the carrier currents due to the break is automatically compensated for, due to the special adjustment of the spare CC units or to the insertion of the repeater, and if this compensation suffices, the system continues to operate properly and the fault is manifested only by the lighting of lamps 42 and 72. Further compensation may be provided, if necessary, by the usual procedure of energizing the office changeover relay whenever a fault occurs, as already explained, while if the compensation is excessive, the system may readily be adjusted by the maintainer to restore the normal transmission level, as will readily be understood. When a break occurs in the line circuit for one of the remote sections, communication is maintained with only those stations in that section which are located on the office side of the break, so that by transmitting control codes to each of the stations in the defective section and observing which of these transmit return indications, the approximate location of a break in the line can be readily ascertained.

In view of the foregoing description it will be clear that the apparatus of my invention provides facilities by which a centralized traffic control system covering an extensive territory may be maintained in substantially continuous service irrespective of the occurrence of a wide variety of possible faults in the communication line circuits or in the apparatus connected thereto.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a remote control system, a two wire line circuit extending from an office to a remote station, a changeover relay at said station normally energized by direct current supplied over said line circuit from a source at the office, code receiving means at the office responsive to carrier current energy supplied over said line circuit, means at the station for supplying to said line circuit carrier current energy of one value when the changeover relay is picked up and of a higher value when the changeover relay is released, whereby the release of said changeover relay due to a fault in said line circuit results in an increase in the carrier current energy supplied to the line circuit to compensate in part at least to the increased transmission loss due to the fault.

2. In a remote control system, a two wire line circuit extending from an office to a remote station, a changeover relay at said station normally energized by direct current supplied over said line circuit from a source at the office, code receiving means at the station responsive to carrier current energy supplied over said line circuit, means at the office for supplying to said line circuit carrier current energy of a value normally sufficient to operate said receiving means, and means for rendering said receiving means responsive to carrier current energy of a lower value when said changeover relay is released,

whereby the release of said changeover relay due to a fault in said line circuit increases the transmission gain in said receiving means to compensate in part at least to the increased transmission loss due to said fault.

3. In a remote control system, a two wire line circuit extending from an office to a remote station, a changeover relay at said station normally energized by direct current supplied over said line circuit from a source at the office, code receiving means at the office responsive to carrier current energy supplied over said line circuit, two sets of similar apparatus at the station for supplying carrier current energy to the line circuit to which said receiving means is responsive, one of which sets is arranged to supply energy of a normal value when the changeover relay is picked up, and the other to supply energy of a higher value when the changeover relay is released, so that if said changeover relay is released due to a fault in line circuit the carrier current energy supplied thereto is increased to compensate in part at least to the increased transmission loss due to the fault, and manually operable means at the office for controlling the current supplied over said line circuit to render said changeover relay subject to manual control from said office.

4. In a remote control system, a two wire line circuit extending from an office to a remote station, a changeover relay at said station normally energized by direct current supplied over said line circuit from a source at the office, code transmitting means at the office for supplying coded carrier current to said line wires, two sets of similar apparatus at the station for receiving said coded carrier currents, one of which is responsive to the carrier current normally supplied to the line circuit and is connected thereto when the changeover relay is picked up, the other being connected to the line circuit when the changeover relay is released and adjusted to respond at a lower energy level to compensate for the impaired transmission due to a line fault, manually operable means at the office for controlling the direct current supplied to said line wires to enable either of said sets of apparatus to be connected to said line wires by the manual control of said changeover relay.

5. In a remote control system, a two wire line circuit comprising a first section extending from an office to a first station and a second section extending from said first station to a second station, a changeover relay at said first station normally energized by direct current supplied over the first section of said line circuit from a source at the office, code receiving means at the office responsive to a carrier current energy supplied over said line circuit, means at the second station for supplying carrier current to the second section of said line circuit, a repeater at said first station for supplying increased carrier current energy to the first section of said line circuit when supplied with carrier current energy from the second section of said line circuit, and means for establishing connections to pass carrier current from the second section to the first section when the changeover relay is energized and to interpose said repeater when the changeover relay is released, whereby the release of said changeover relay due to a fault in said first section results in an increase in the carrier current energy supplied thereto to compensate in part at least to the increased transmission loss due to the fault.

6. In a remote control system, a two wire line

circuit comprising a first section extending from an office to a first station and a second section extending from said first station to a second station, a changeover relay at said first station normally energized by direct current supplied over the first section of said line circuit from a source at the office, code receiving means at the second station responsive to carrier current energy supplied over said line circuit, means at the office for supplying carrier current to the first section of said line circuit, a repeater at said first station for supplying increased carrier current energy to the second section of said line circuit when supplied with carrier current energy from the first section of said line circuit, and means for establishing connections to pass carrier current from the first section to the second section when the changeover relay is energized and to interpose said repeater when the changeover relay is released, whereby the release of said changeover relay due to a fault in said first section results in an increase in the carrier current energy supplied to the second section to compensate in part at least to the increased transmission loss due to the fault.

7. In a remote control system, a two wire line circuit comprising a first section extending from an office to a first station and a second section extending from said first station to a second station, a first and a second changeover relay at said first station normally energized by direct current supplied over the first section of said line circuit from a source at the office, the first changeover relay being responsive to current above a minimum value of one polarity only, and the second to current of a lower value of either polarity, manually operable means at the office for independently governing the polarity and value of said current to selectively control said relays, two sets of code receiving means at the office selectively responsive to carrier current energy of a first and of a second frequency, respectively, supplied to said line circuit, two sets of apparatus at said first station for supplying carrier current of said first frequency to the line wires, one of which sets is arranged to supply energy of a normal value when one changeover relay is picked up and the other to supply energy of a higher value when said one changeover relay is released, a repeater at said first station for supplying increased carrier current energy to the first section of said line circuit when supplied with carrier current energy from the second section of said line circuit, means at said second station for supplying carrier current energy of said second frequency to the second section of said line circuit, and means controlled by the other changeover

- relay at said first station for passing carrier current from the second section to the first section when such relay is picked up and for interposing said repeater when such relay is released.
- 5 8. In a remote control system, a two wire line circuit comprising a first section extending from an office to a first station and a second section extending from said first station to a second station, a first and a second changeover relay at said first station normally energized by direct current supplied over the first section of said line circuit from a source at the office, the first changeover relay being responsive to current above a minimum value of one polarity only, 10 and the second only to current of a lower value of either polarity, manually operable means at the office for independently governing the polarity and value of said current to selectively control said relays, two sets of code transmitting apparatus at the office for supplying coded carrier current of a first and of a second frequency, respectively, to the first section of said line circuit, two sets of receiving apparatus at said first station selectively responsive to carrier currents of 15 said first frequency, one of which is responsive to the current normally supplied to the first section of the line circuit and is connected thereto when one changeover relay is picked up, the other being connected to said first line circuit 20 section when said one changeover relay is released, said other set being adjusted to respond at a lower energy level to compensate for the impaired transmission due to a line fault, a repeater at said first station for supplying carrier current of said second frequency and increased energy to the second section of said line circuit when supplied with carrier current of said second frequency from the first section, receiving apparatus at said second station responsive to carrier 25 current of said second frequency in said second line circuit section, means controlled by the other changeover relay at said first station for passing carrier current of the second frequency from the first section to the second section when such relay is picked up and for interposing said repeater when such relay is released, whereby such changeover relay may be released manually to 30 increase the carrier current energy supplied to the second section without increasing that supplied to the first section to compensate for a fault in said second section and both changeover relays release in the event of a fault in the first section to effect automatic compensation for such fault, 35 with respect to carrier currents of both frequencies.

PAUL K. ECKHARDT.
